MODULAR CONSOLE FOR A DENTAL OPERATORY

John M. Schwartz, Des Moines, Iowa, assignor to
Den-Tal-Ez Mfg. Co., Des Moines, Iowa

Filed Feb. 7, 1972, Ser. No. 224,384

Term of patent 14 years

Int. Cl. D24—01

U.S. Cl. D24—1 B

FIG. 1

FIG. 2

FIG. 3FIG. 1 is a front perspective view of a modular console for a dental operatory showing my new design;

FIG. 2 is a top view; and

FIG. 3 is a rear perspective view looking toward the end of the console opposite the end shown in FIG. 1.

I claim:

The ornamental design for a modular console for a dental operatory, substantially as shown.
